UNITED STATES PATENT OFFICE.

DANIEL O. WARD, OF OAK PARK, ILLINOIS; NELLIE LEE WARD ADMINISTRATRIX OF
SAID DANIEL O. WARD, DECEASED.

SELF-LOCKING NUT AND PROCESS OF MAKING SAME.

1,087,056.

Specification of Letters Patent.

Patented Feb. 10, 1914.

Application filed March 3, 1913. Serial No. 751,855.

To all whom it may concern:

Be it known that I, DANIEL O. WARD, a citizen of the United States, residing at Oak Park, in the county of Cook and State 5 of Illinois, have invented certain new and useful Improvements in Self-Locking Nuts and Processes of Making Same, of which the following is a specification, reference being had therein to the accompanying drawing.

10 This invention relates to an improvement in self-locking nuts and an improved process for making the same.

One of the objects of the present invention is the provision of a self-locking nut of 15 a simple and efficient construction which is stronger and more durable than nuts of a somewhat similar character heretofore suggested in this art.

20 A further object of the invention is the provision of an improved process adapted to render the manufacture of the improved nuts above referred to, economical and commercially feasible.

The invention, both as respects the process 25 and its resultant product, will be more readily understood from the detailed description hereinafter contained when read in connection with the accompanying drawings forming a part hereof, and wherein,

30 Figure 1 is a perspective view of a self-locking nut constructed in accordance with the present invention; Fig. 2 is a cross section thereof; Figs. 3 and 4 are perspective views of a bar of metal stock showing the 35 different shapes to which said bar is rolled during the manufacture of the improved self-locking nut; and Fig. 5 is a perspective view of one of the nut blanks as obtained from the bar of metal stock shown in Fig. 3.

40 Referring now more particularly to the drawings, wherein like reference letters designate corresponding features in the several views, it will be seen that the improved self-locking nut comprises a body A which 45 is provided with a centrally disposed threaded opening a extending therethrough for the reception of an ordinary threaded bolt, said body being provided in opposite sides thereof with grooves a' which extend

50 transversely across the body of the nut and inwardly so as to intersect the opening a extending centrally therethrough, so that there is provided at each side of the nut, above the main body portion thereof, and 55 separated from said main body portion by

the grooves a',—sections A' which extend upwardly at a slight angle to the main body portion of the nut, so that when the nut is threaded onto a bolt, and the sections A' are forced downwardly toward the main body 60 portion of the nut, said nut will be locked firmly in position on the bolt, the thread being formed through the body and sections A' after the latter are deflected away from the body, so that the threaded portions 65 within the sections are displaced relative to the thread of the bolt to create a binding engagement therebetween when the sections are forced toward the body, in the application of the nut, as stated.

70 The particular novelty of the present construction is that the metal of the nut is condensed, as at a², adjacent the grooves a' formed therein, thus materially increasing the strength of the sections A' which 75 have to be bent when the nut is used, and consequently greatly lengthening the life of the nut.

70 In forming the improved self-locking nut, a bar of stock metal is first heated and treated by suitable rolls to cause it to assume the shape shown in Fig. 3, that is, the bar is rolled to a substantially rectangular cross section; then a groove or channel b is rolled in each edge thereof, adjacent the upper 85 surface of the bar by a single or by successive rolling operations (as at x), said grooves extending inwardly of the central portion of the bar. The bar of metal stock is then subjected to further treatment by 90 suitable rolls—a single or successive rolling operation (as at y)—to cause the deflection of the portions of the bar above the grooves b which have been rolled in the sides thereof. The bar, after this operation, will appear as in Fig. 4. After being rolled to this form, the bar B is placed in a bulldozer machine, and the nut blanks are cut therefrom, the bolt receiving opening being formed simultaneously in the nut blank as it is cut 95 from the bar B.

100 To complete the self-locking nut, the nut blanks are placed in a threading machine and the bolt receiving openings thereof threaded in the usual manner. As the bar of metal stock is brought to its proper form entirely by rolling, it will be seen that the process 105 can be practiced much more readily, without waste, and more economically than those processes in which it is necessary to cut 110

away a portion of the metal, or to saw into the sides,—both slow and expensive operations. Furthermore, by the particular process herein described, a superior and 5 more durable article of manufacture is obtained than is the case where the method of manufacture involves the cutting out, or sawing away of the metal, since by rolling the metal to form the channels in the sides 10 of the nut, the metal adjacent to said channels is condensed, which materially strengthens the nut where it would otherwise be weakest, namely, along the lines of juncture between the locking portions A' and the 15 main body portion of the nut.

It is to be observed that by reason of forming the nut from a solid blank, as distinguished from folding over a nut from a sheet of metal, no portions of the body of 20 metal are weakened during the process, while at the same time the condensed metallic portions as hereinbefore set forth are obtained. It will also be appreciated that not only are the lines of juncture between 25 the locking portions A' and the main body of the nut reinforced by the condensing of the metal thereat, but under the compressing operation the flanges *a* are, of course, strengthened to the extent that some of the 30 metal will also be compressed and taken up in the flanges as well as the adjoining surface of the body, although, of course, the greatest condensed portion will be at the base of the groove or line of juncture between 35 the flange and body, as stated.

While I have herein disclosed a specific embodiment of the invention, it will be apparent to persons skilled in the art that said invention is capable of embodiment in other 40 forms and devices, as may be in keeping with the hereto appended claims.

I claim:—

1. A self-locking nut comprising a main body portion provided with a threaded bolt 45 receiving aperture, and with a transverse groove extending inwardly from one side thereof, the metal of said nut adjacent said groove being condensed and the metal therebeyond being of at least the normal density 50 of the blank from which the nut is formed.

2. A self-locking nut comprising a main body portion having a threaded bolt receiving aperture, said main body portion being provided with transverse grooves extending 55 inwardly from opposite sides thereof to form locking portions spaced from the main body portion of said nut, the metal of the nut adjacent the connection of said locking portions with the main body portion there- 60 of being condensed.

3. A self-locking nut comprising a main body portion, and a bendable locking portion integral with said main body portion and spaced therefrom, said nut being pro- 65 vided with a bolt receiving aperture ex-

tending through the main body portion and said locking portion, and the metal of said nut adjacent the connection of the locking portion with the main body portion thereof being condensed.

4. The process of making self-locking nuts consisting in compressing the metal of a metallic bar to form an inwardly extending groove in one side thereof, dividing the bar into individual nut blanks, and forming in each of the nut blanks a threaded bolt receiving opening. 70

5. The method of forming self-locking nuts, consisting in rolling a metal bar to provide an inwardly extending groove in one side of said bar, further rolling the bar to flare the portion of said bar above the groove, dividing the bar into individual nut blanks, providing each blank with an opening which extends therethrough, and threading the opening thus formed in each of the blanks. 75

6. The method of forming self-locking nuts consisting in rolling a bar of metal to provide inwardly extending grooves in the 80 sides thereof, dividing the bar thus formed into individual nut blanks, and forming a threaded bolt receiving opening in each of the nut blanks. 85

7. The method of forming self-locking nuts consisting in rolling a bar of metal to provide inwardly extending grooves in the opposite sides thereof, bending upwardly the portions of said bar positioned above said grooves, dividing the bar into individual nut blanks, forming an opening through each of said blanks, and threading the openings in the nut blanks. 90

8. The method of forming a self-locking nut consisting in compressing the metal of a nut blank to form oppositely disposed 100 inwardly extending grooves in the sides thereof, and forming a threaded bolt receiving opening in said blank. 105

9. The process of making self-locking nuts consisting in compressing the metal of a metallic bar to form an inwardly extending groove in one side thereof, dividing the bar into individual nut blanks, and forming each of the nut blanks a threaded bolt receiving opening which intersects the groove 110 in one side thereof. 115

10. The method of forming self-locking nuts, consisting in rolling a metal bar to provide an inwardly extending groove in one side of said bar, further rolling the bar to flare the portion of said bar above the groove, dividing the bar into individual nut blanks, and simultaneously providing each blank with an opening which extends therethrough and intersects the groove in the side thereof, and threading the opening thus formed in each of the blanks. 120

11. The process of making self-locking nuts consisting in the following steps, to 125

wit, compressing metal of the metallic bar to form an inwardly extending groove in one side thereof, dividing the bar into individual nut blanks, forming in each of the 5 blanks a threaded bolt receiving opening extending into both of the grooved portions so that the opening intersects the groove, and deflecting the grooved portions with respect to each other.

10 12. The process of making locking devices comprising the condensing of a portion of a metal blank to space a wing from the body thereof and strengthen the line of juncture therebetween, and aperturing the 15 blank to constitute a bolt opening, substantially as described.

13. The process of making locking devices comprising the spacing of an integral wing from a metal body, and condensing 20 the metal of a portion of the body at the point of juncture between the body and wing, substantially as described.

14. A locking device of the character de-

scribed comprising a metal body, a wing integral therewith and spaced therefrom, 25 the juncture between the body and wing being constituted by condensed portions of the metal and the metal therebeyond being of, at least the normal density of the blank from which the nut is formed, substantially 30 as described.

15. A locking device of the character described comprising a metal body, a wing integral therewith and spaced therefrom, the juncture between the body and wing being 35 constructed by condensed portions of the metal, said wing being also formed by condensed portions of said metal, substantially as described.

In testimony whereof I affix my signature 40 in presence of two witnesses.

DANIEL O. WARD.
